UNITED STATES PATENT OFFICE.

FERDINAND P. SCHOENHARDT, OF MERIDEN, CONNECTICUT, ASSIGNOR TO EDWARD MILLER & COMPANY, OF MERIDEN, CONNECTICUT, A CORPORATION OF CONNECTICUT.

DESIGN FOR A LIGHTING-FIXTURE.

46,698.

Specification for Design.

Patented Nov. 24, 1914.

Application filed August 14, 1914. Serial No. 856,877. Term of patent 7 years.

To all whom it may concern:

Be it known that I, FERDINAND P. SCHOENHARDT, a citizen of the United States, residing at Meriden, New Haven county, State of Connecticut, have invented a new, original, and ornamental Design for Lighting-Fixtures, Including Shells, Shades, and the like, of which the following is a specification, reference being had to the accompanying drawing, forming a part thereof, in which drawing—

I claim:

The ornamental design for a lighting fixture, as shown.

FERDINAND P. SCHOENHARDT.
